UNITED STATES PATENT OFFICE

2,150,003

CURTAIN STRETCHER

John F. Lizak, McKeesport, Pa.

Application September 9, 1937, Serial No. 163,050

2 Claims. (Cl. 45—24)

My invention relates to stretchers for supporting and holding curtains and the like in a taut condition while drying.

One object of my invention is to provide a stretcher having improved means for detachably holding the curtains in place and which are readily adjustable on the stretcher frame.

Another object of my invention is to provide improved means for connecting and supporting the members of the stretcher frame.

One form which my invention may take is shown in the accompanying drawing wherein Figure 1 is a face view of a stretcher, with one of the joint connections shown in section; Fig. 2 is an end view thereof; Fig. 3 is a rear view, on an enlarged scale, showing one of the connecting clamps for the frame; Fig. 4 is an enlarged view taken on the line IV—IV of Fig. 1; Fig. 5 is an enlarged view taken on the line V—V of Fig. 1; Fig. 6 is a face view, on an enlarged scale, of one of the curtain-gripping or clamping elements of Fig. 1; Fig. 7 is a side view thereof showing the same in curtain-gripping position, and Fig. 8 is a view showing it in released position.

The frame comprises upper longitudinal or edge bars 10; lower longitudinal bars 11; end bars 12 and 13; legs 14, and a spreader bar 15.

For smaller curtains, one of the bars 10 and one of the bars 11 may be omitted, but ordinarily a pair of bars 10 and a pair of bars 11 will be employed. The adjacent ends of such respective pairs of bars are connected by a pair of dowel pins 16 which have snug-driven fit with one of the bars and are insertable into holes in the other bar. The spreader bar 15 has a pair of projecting dowel pins 17 at its upper end, which enter holes in the bars 10 and serve to hold said bars snugly in end-to-end relation. The bar 15 is provided with a longitudinally-extending slot 18 through which extends a bolt 19 that carries a block 20 and a wing nut 21. The nut 21 is utilized to firmly hold the block 20 in desired set positions on the bar 15, and the block 20 is provided with a pair of dowel pins 21a which enter holes in the bars 11 to hold the ends of such bars in abutting relation. The member 15 serves to hold the bars 10 and 11 apart in parallelism against the tension of a stretched curtain.

The end bar 13 is connected at its upper end to one of the bars 10, by means of a clamping plate 23 whose upper end is flanged to overlie the upper edge of the bar 10, and which is provided with a pair of slots through which guide screws 24 and 25 extend, the screws being driven into the bar 13. A lever 26 has a camming disc portion

27 formed thereon and rotatably supported by the screws 25. Lugs 28 and 29 are struck up from the plate 23 in position to be engaged by the edge of the camming disc 27. It will be seen that when the lever 26 is oscillated it will effect movement of the plate 23 into and out of clamping engagement with the bar 10. The bar 13 is connected in a similar manner to one of the bars 11, the clamp at that point being actuated by a lever 30 which corresponds to the lever 26, and another similar clamping connection is provided between the bar 12 and the other bar 10, the last-named clamp being operated by a lever 31.

Connection between the bar 12 and one of the bars 11 is effected by a clamp 32 which, as shown more clearly in Fig. 4, has a portion 33 extending beneath and to the outer side of the bar 11, and a rearwardly-extending portion 34 which is extended at 35 to the rear side of the bar 12. A thumb screw 36 is carried by the element 33 for holding the bars 11 and 12 in clamped engagement. It will be seen that the clamp 32 can be placed in position readily at any point, without sliding it from the extreme end of one of the bars 11, since a simple horizontal movement will bring the parts 34 and 35 into embracing engagement with the bar 12, and a simple vertical movement will bring the part 33 into embracing engagement with the bar 11.

The clamping elements are preferably of metal, and the frame bars preferably formed of wood.

The bars 10, 11, 12 and 13 have longitudinally-extending grooves whose walls are undercut, or which are of somewhat more than 180° in curvature, for the reception of curtain-gripping elements 37, which may be made of either wood or metal, but preferably formed of wood. Each element 37 has a partially cylindrical portion 38 that is slideable in the groove and can oscillate or tilt therein. A lever 39 is pivotally connected to the member 37 and has a camming surface formed on its inner end so that when said lever is turned from the position shown in Fig. 8 to the position shown in Fig. 7, the finger-like extensions 40 of the gripping device will be brought into engagement with an edge of a curtain.

The gripping members 37 can be cheaply made by shaping a long wooden bar so that in cross section it will correspond to the contour of the members 37 as viewed in Figs. 7 and 8. Thereafter the bar can be moved transversely against gang saws to form slots for the reception of the levers 39. The bar can then be moved against other gang saws which will divide it transversely into a plurality of elements 37, after which the

levers 39 can be inserted and pivot pins or nails 41 driven into place to connect the levers to the gripping elements.

I claim as my invention:

- 5 1. A curtain stretcher comprising frame bars held in assembled relation and provided with undercut grooves extending longitudinally thereof, gripping elements having enlarged projections extending into said grooves and slideable longitudinally thereof, and camming devices operable to rock the said gripping devices into position to grip and hold the curtain against the said bars.
- 10 2. A curtain stretcher comprising frame bars held in assembled relation and provided with un-

dercut grooves extending longitudinally thereof, gripping elements having enlarged projections extending into said grooves and slideable longitudinally thereof, curtain-gripping extensions on said elements, other extensions formed thereon and projecting oppositely to the first-named extensions, and camming levers positioned in the second-named extensions for engagement with the adjacent faces of the side bars whereby upon operation of the levers the gripping elements will 10 be rocked to cause the first-named extensions to grip and hold a curtain against the said bars.

JOHN F. LIZAK.
